UNITED STATES PATENT OFFICE.

JULES MASSON, OF ASNIÈRES, AND JULES LOCHELONGUE, OF PARIS, FRANCE, ASSIGNORS TO JAMES SLOPER, OF BOIS-DE-COLUMBES, AND FREDERIC DE REISSET, OF PARIS, FRANCE.

RAILWAY-SWITCH.

SPECIFICATION forming part of Letters Patent No. 601,352, dated March 29, 1898.

Application filed September 24, 1897. Serial No. 652,826. (No model.) Patented in France August 1, 1896, No. 258,574; in Belgium December 14, 1896, No. 125,178, and in England December 15, 1896, No. 28,737.

To all whom it may concern:

Be it known that we, JULES MASSON, a resident of Asnières, (Seine,) and JULES LOCHELONGUE, a resident of Paris, France, citizens 5 of the Republic of France, have invented certain new and useful Improvements in Railway-Switches, (for which we have obtained Letters Patent of Belgium, No. 125,178, dated December 14, 1896; of France, No. 258,574, 10 dated August 1, 1896, and of Great Britain, provisional, No. 28,737, dated December 15, 1896,) of which the following is a specification, reference being had to the accompanying drawings, forming a part thereof.

15 The object of our invention is to provide simple and effective means for controlling a railway-switch, so that it shall be at all times locked positively when it is approached by a locomotive or car from the point and shall 20 be automatically unlocked and released to permit the free passage of a locomotive or car from the main line or from the siding when such locomotive or car passes over the switch from the heel. At the same time provision is made whereby the switch can be 25 operated by hand to direct the approaching locomotive or car upon the siding or upon the main line, as desired.

We will describe our invention in detail 30 hereinafter with reference to the accompanying drawings, in which—

Figure 1 is a plan view of a portion of a railway track and switch to which our invention is applied in a convenient and practical form. Fig. 2 is a side view of the parts shown in Fig. 1, but with the switch-stand removed and the switch-rod in section. Fig. 3 is a detail view in section on the plane indicated by the line $x-x$ of Fig. 1. Fig. 4 is a 40 detail view in section on the plane indicated by the line $y-y$ of Fig. 1. Fig. 5 is a detail view, partly in side elevation and partly in section, illustrating the application of a spring in place of a weight, as shown in Figs. 1 and 2.

45 In the arrangement represented in the drawings the fixed rails of the main track are represented at A A and those of the siding at B B, while the movable switch-tongues

A' and B', coupled by links a b or otherwise and suitably tapered, form continuations of 50 the respective fixed rails of the main line and the siding; but it will be obvious that the parts may be arranged in any desired manner, this invention having to do with the means for moving and locking a movable 55 switch-tongue.

As represented in Fig. 3, the movable switch-tongue B' may be connected by a switch-rod C to a suitable switch-lever C', which may be arranged in any convenient manner and is 60 represented in said figure as having applied thereto a suitable counterweight c and as pivoted upon a suitable base or standard c'. Any desired means, however, may be employed for the operation of the switch by hand without 65 affecting the application of our present improvement to the switch.

To provide for the locking of the movable switch-tongue, we have represented said tongue as having a projecting stud or tenon 70 b', which is formed with an eye b² and is adapted to enter and project through a suitable hole a' in the fixed rail A or in any other fixed abutment which may be provided for the purpose. A locking-pin D is arranged to 75 enter the eye b² in the stud or tenon b' or otherwise to engage the same to lock the movable tongue B' positively in position. The said locking-pin D is adapted to be withdrawn automatically to release the switch-tongue whenever a locomotive or car approaches the switch from the rear or from the heel, a lever or system of levers being provided for this purpose, so that the locking-pin can be withdrawn by the locomotive or 80 car at a suitable distance from the switch. In the drawings we have shown a long lever E, which is mounted in close proximity to the fixed rail A and which normally stands for a portion of its length slightly above the bearing-surface of the rail, so that it will be depressed by a wheel of the locomotive or car as it rolls over the rail and thereby will withdraw the pin D, which is represented as carried directly upon the free end of said lever 85 E. The said lever is held in its normal posi- 90 95

tion by any suitable means, such as a lever F, which in the construction shown is represented as comprising a short shaft f, mounted in suitable bearings, an arm f', which underlies the lever E, and an arm f'', to which may be applied a counterweight f³, adjustable to secure the proper action and held in place by a set-screw f⁴. The arms f' and f'' may also be adjustable upon the shaft f, being held in 10 adjusted position by set-screws f⁵.

It will now be readily understood that the locking-pin D normally holds the switch-tongue B' positively from movement and that when the locomotive or car approaches the 15 switch from the rear or heel end said locking-pin is automatically withdrawn and the said switch-tongue B' yields to permit the wheels of the locomotive or car to pass along the fixed rail A, the said switch-tongue being 20 turned to its normal position after the locomotive or car has passed by the counterweight or spring applied to the switch-lever C' and being immediately engaged again by the locking-pin D.

25 Should it be desired to move the switch-tongue by hand, it will obviously be necessary first to withdraw the locking-pin. For this purpose we have provided a foot-lever G, mounted in close proximity to the switch-30 stand and consisting, in the arrangement shown, of a short shaft g, mounted in suitable bearings, an arm g', underlying the counterweight f³ of the lever F, and an arm g'', having a foot-piece g³ in convenient position to be pressed by the switchman's foot as he takes position to operate the lever C'. Such action lifts the counterweight f³ and permits the weight of the lever E of itself to withdraw the locking-pin D and thereby leave the 40 switch-tongue free to be shifted.

In Fig. 5 we have represented a spring applied to the locking-lever E in place of the lever F and its counterweight. As there represented a rod F' is applied to the locking-lever E and is guided by a bracket f⁶. A 45 spring f⁷ bears at one end against a suitable support and at the other against a collar or shoulder f⁸, formed on or secured to the rod F', thereby normally maintaining the locking-lever E in its elevated position. A bell-50 crank lever H is suitably supported in engagement with the rod F' and may be con-

nected by a link h to a suitable foot-lever in proximity to the switch-stand, whereby the locking-lever may be drawn down against the 55 pressure of the spring f⁷ to release the switch-tongue whenever it is desired to shift the latter by hand.

It will be understood, of course, that we do not intend to restrict our invention to the 60 precise construction and arrangement of parts shown and described herein.

We claim as our invention—

1. In a railway-switch, the combination of a movable switch-tongue, a locking-pin to retain the same positively against movement, a locking-lever mounted in proximity to the track to be operated by a passing locomotive or car to withdraw said locking-pin, means to hold said lever normally in elevated position and means to depress said lever at will to withdraw said locking-pin, substantially as shown and described. 65

2. In a railway-switch, the combination of a movable switch-tongue, a locking-pin to retain the same positively against movement, a locking-lever mounted in proximity to the track to be operated by a passing locomotive or car to withdraw said locking-pin, a counterbalanced lever to hold said locking-lever 75 normally in elevated position and a lever to move said counterbalanced lever and release the locking-lever, and means to shift said switch-tongue at will, substantially as shown and described. 70

3. In a railway-switch, the combination of a movable switch-tongue, a counterbalanced switch-lever connected thereto, a locking-pin to retain said switch-lever positively against movement, a locking-lever mounted in proximity to the track to be operated by a passing locomotive or car to withdraw said locking-pin, a counterbalanced lever to hold said locking-lever normally in elevated position, and a foot-lever to move said counterbalanced 80 lever and release the locking-lever, substantially as shown and described. 85

This specification signed and witnessed this 11th day of September, A. D. 1897.

JULES MASSON.

JULES LOCHELONGUE.
